FINGER RING

Jacob Stein, 210 E. Broadway, New York, N.Y. 10002

Filed Feb. 22, 1971, Ser. No. 117,885

Term of patent 14 years

Int. Cl. D11—01

U.S. Cl. D45—10

FIG. 1

FIG. 2

FIG. 3

FIG. 1 is a top plan view of a finger ring showing my new design;

FIG. 2 is a front view thereof, the back being identical in appearance; and

FIG. 3 is a side view thereof, both sides being identical in appearance.

I claim:

The ornamental design for a finger ring, as shown and described.
